CLAIM

The ornamental design for a display shelf, as shown and described.

DESCRIPTION

FIG. 1 is a top and front perspective view of a display shelf showing a first embodiment of our new design;

FIG. 2 is a front view thereof;

FIG. 3 is a rear view thereof;

FIG. 4 is a right side view thereof, the left side view being a mirror image of the right side view;

FIG. 5 is a top view thereof; and

FIG. 6 is a bottom view thereof.

FIG. 7 is a top and front perspective view of the display shelf of FIG. 1 with additional unclaimed environmental subject matter illustrating one example use of the display shelf;

FIG. 8 is a front view thereof;

FIG. 9 is a rear view thereof;

FIG. 10 is a right side view thereof, the left side view being a mirror image of the right side view;

FIG. 11 is a top view thereof; and,

FIG. 12 is a bottom view thereof.

In the drawings, the broken lines depict unclaimed subject matter only and form no part of the claimed design.

1 Claim, 12 Drawing Sheets
